UNITED STATES PATENT OFFICE

2,153,608

SKIVING MACHINE

Floyd W. Backus, St. Louis, Mo., assignor to
 United Shoe Machinery Corporation, Paterson, N. J., a corporation of New Jersey

Application November 2, 1937, Serial No. 172,413

5 Claims. (Cl. 69—16)

This invention relates to skiving machines and is herein illustrated as embodied in a machine for skiving parts of the uppers of boots and shoes.

5 In the manufacture of shoes, it is sometimes desirable to produce rapidly in succession scarves of three different predetermined inclinations and widths, for example upon the same piece of leather. In prior machines two such scarves have been produced by providing means for varying the relative angular position of the knife and the work-supporting feed roll of a leather skiving machine, such means including a controlling member movable at the will of the operator between two stops. When the member is moved into engagement with one stop a scarf of a given width and inclination is produced, and when the member is moved into engagement with the other stop, a different scarf is produced.

20 To permit scarves of three different predetermined inclinations to be produced at will by rapid adjustment of the controlling member, there is provided, according to the present invention, a third stop so that the relative angular position 25 of the knife and the work support may be instantly and accurately changed from one position to either one of two others.

Referring to the accompanying drawings,

30 Fig. 1 is a front elevation of a portion of a skiving machine in which the present invention is embodied;

Fig. 2 is a detail in elevation of the knife and feed roll, a piece of work being shown in process of being skived, and the roll being shown in three 35 different angular positions;

Fig. 3 is a plan of a short Blucher vamp having upon its margins scarves of three different widths and inclinations;

Fig. 4 is a detail in elevation on enlarged scale 40 of the third stop and the controlling member with which it cooperates;

Fig. 5 is a view principally in front elevation of a modified form of a third stop; and

Fig. 6 is an end elevation of the third stop.

45 In skiving the margins of pieces of leather it is frequently desirable to be able to produce rapidly in succession three scarves of different inclinations and widths and to produce them in any desired order. For example, the Blucher vamp shown in Fig. 3 has a wide scarf A of gradual inclination along its forward end, a narrow scarf B of steep inclination along its throat, and two scarves C, D along the inside of the 50 wings which are alike and are intermediate as

to width and inclination between the scarf A and the scarf B.

The illustrated machine is or may be similar to the machine of United States Letters Patent No. 1,866,918, granted July 12, 1932, upon an application filed in the name of Milton H. Ballard; and before proceeding to describe what is new, a brief description of the old construction will be given. The machine comprises a rotary disk knife 7, a feed roll 9, a feed disk 11 and an edge 10 guide and presser 13. The feed roll shaft is rotatable in a block 17 which is adjustable substantially horizontally in a carrier 19, said carrier being adjustable in a curved guideway the axis of curvature of which passes through the upper inner corner of the roll when the horizontally adjustable block 17 is in the position shown. In order to provide means for tilting the feed roll carrier 19 by sliding it in its curved guideway, this carrier is connected by a link 21 to one arm 20 of a bell-crank lever pivoted at 27 to the frame of the machine, the other arm 29 of the bell-crank lever having pivoted to it the upper end of a treadle rod 31. The upper end of the arm 25 carries a block 23 which swings with the arm. Attached to the lower end of the treadle rod 31 is a toe-and-heel treadle, not shown. When the heel end of this treadle is depressed to push up the rod 31, the block or controlling member 23 is swung to the left. When the toe end is depressed to pull the rod 31 down, the block 23 is swung to the right. The position of this controlling member thus determines the angular position of the feed roll and hence the inclination of the scarf which will be produced. Two adjustable stops 33, 35, threaded on a small rod 38, limit the extent of movement of the controlling block 23. Thus the feed roll may quickly be moved to and held in either one of two predetermined angular positions. The feed disk 11 is 40 mounted upon a bracket which is supported by the feed roll carrier 17, and consequently the relation between the feed disk and the feed roll remains unchanged. The work 100 is fed away from the observer in Figs. 1 and 2, the controlling block 23 being held in engagement with one or other of the stops 33, 35. Referring now to Fig. 2, three different angular positions of the feed roll are shown, the tipping of the roll having been somewhat exaggerated for the purpose 45 of illustration. In the left-hand full line position indicated at AA a wide scarf of gradual inclination such as the scarf A of Fig. 3 will be produced, and the controlling block 23 will be in engagement with the left-end stop 33 which has 50

previously been adjusted into the proper position. In the right-hand dot-and-dash position of the roll 9, indicated at BB in Fig. 2, the treadle rod 31 will have been pulled down to hold the controlling block 23 against the right-end stop 35, and a very narrow scarf of much greater inclination, such as the scarf B of Fig. 3, will be produced. The machine as thus far described is or may be substantially the same as the machine of the patent to which reference is made for details not herein described.

In order to permit the feed roll to be moved into a predetermined intermediate position such, for example, as that indicated at CD in Fig. 2, to produce scarves such as those indicated at C and D in Fig. 3, a third stop is provided which may be adjusted so as to permit the control block 23 to be held in any desired position between the stops 33 and 35. This stop takes the form of a thin flat resilient member 37 the right-hand end of which is fastened by a clamping screw 39 and a clamping plate 41 to a stationary bracket 42. The stem of the screw passes through a slot in the stop 37 so that the stop may be adjusted lengthwise. The stop 37 has near its left-hand end a projection 43 adapted to engage a small recess 45 formed in the top of the block when the stop is moved beneath it. Assuming now that it is desired to move the feed roll into and hold it in an intermediate angular position such as that indicated at CD in Fig. 2, the third stop 37 will be adjusted into a position in which the projection 43 will snap into the recess 45 in the block when the roll 9 has been swung into the desired intermediate position. Since the stop 37 is resilient, the operator, by exerting sufficient force upon the treadle rod 31, may move the block 23 from engagement with the stop 33 past the stop 37 and into engagement with the stop 35 and back again if he so desires. However, by modulating the force which is used to manipulate the treadle rod 31, the operator may cause the stop 37 to be effective when desired. In the operation of the machine, for example upon the Blucher vamp shown in Fig. 3, the operator may make the various scarves in different orders. The scarf A may be made first with the block 23 in engagement with the stop 33; the scarf B may next be made with the block 23 in engagement with the stop 35; and, finally, the scarves C and D may be made with the block in engagement with the stop 37. The scarves may also be made in the order A, C, B, D or in whatever order the operator may desire.

A modified construction is shown in Figs. 5 and 6. In this construction the threaded rod 38 of Fig. 1 has been replaced by a longer threaded rod 138, and the control block 23 has been replaced by a control block 123 having no recess in its upper face. This block is mounted, as is the block 23 of Fig. 1, in the upper part of one arm 25 of a bell-crank lever pivoted to the frame at 21, the other arm 29 of the bell-crank lever being pivoted at its upper end to the upper end of the treadle rod 31; and, as in the construction shown in Fig. 1, a link 21 connects the arm 25 with the feed roll carrier. As thus far described, with the exception of the threaded rod 138, and the block 123, the construction is or may be the same as that of the patented machine.

The third or intermediate stop in this modification consists of an arm 51 having a downturned end which may be caused to lie in the path of movement of the block 123. This arm has a hollow hub into which is tightly driven a bearing sleeve 53, said sleeve being rotatably and slid-

ably mounted on the threaded rod 138. A compression spring 54 urges the sleeve 53 and with it the stop 51 to the left as far as a nut 55, threaded on the rod 138, will permit. By turning the nut, the stop 51 may be adjusted lengthwise of the rod 138 so that its downturned end may be caused to occupy various predetermined positions between the stops 33 and 35. The stop 51 is normally held in the operative position shown in which it lies in the path of movement of the block 123. To this end the hub of the stop 51 has projecting rearwardly from it an actuating arm 151 to the outer end of which is pivoted the upper end of a second treadle rod 57 which is urged upwardly by a tension spring 59 so as to rock the hub of the stop 51 clockwise as viewed in Fig. 6. A projection 251 on the hub of the stop 51, by contacting with the side of a screw 61, limits the extent of this rocking movement. When the parts are in the normal positions shown the stop 51 is operative with its downturned end in the path of movement of the block 123.

With this construction, the wide scarf A (Fig. 3) of gradual inclination may be produced by holding the treadle rod 57 down to render the third stop 51 inoperative and by moving the treadle rod 31 to its uppermost position, the block 123 then being in engagement with the stop 33. The narrow scarf B of great inclination may now be produced by still holding the treadle rod 57 down and pulling down the treadle rod 31 to cause the block 123 to move to the right (Fig. 5) into contact with the stop 35. The intermediate scarves C, D may then be produced by first permitting the treadle 57 to rise, whereby the stop is moved into operative position and pulling down upon the treadle rod 31, whereupon the block 123 is moved to the left into engagement with the downturned end of the stop 51.

Although the invention has been set forth as embodied in two illustrative constructions, it should be understood that the invention is not limited in the scope of its application to the particular constructions which have been shown and described.

Having described the invention, what I claim as new and desire to secure by Letters Patent of the United States is:

1. A skinning machine having, in combination, a knife, a feed roll, an operator-controlled member movement of which varies the relative angular position of the knife and roll, two stops serving as limits to said movement so as to predetermine the two extreme relative angular positions of the knife and the roll, and a third stop adapted to arrest the movement of said member in a position between the two first-named stops so as to adjust the knife and roll into an intermediate relative angular position.

2. A skinning machine having, in combination, a knife, a feed roll, an operator-controlled member movement of which varies the relative angular position of the knife and roll, two stops serving as limits to said movement so as to predetermine the two extreme relative angular positions of the knife and the roll, and a third stop adapted to arrest the movement of said member in a position between the two first-named stops so as to adjust the knife and roll into an intermediate relative angular position, said third stop being adjustable toward and from the other two.

3. A skinning machine having, in combination, a knife, a feed roll angularly adjustable to vary the width of the scarf produced, a member move-

5. A skiving machine having, in combination, of which changes the angular position of the roll, treadle-controlled means for moving said member, two stops arranged to limit the movements of said member in opposite directions so as to predetermine the two extreme angular positions of the roll, and means for arresting the movement of said member in a position between the two stops so as to adjust the roll into an intermediate predetermined angular position.
10. 4. A skiving machine having, in combination, a knife, a feed roll angularly adjustable to vary the width of the scarf produced, an operator-controlled member movement of which changes the angular position of the roll, two stops arranged to limit the movements of said member in opposite directions so as to predetermine the
- 15.

two extreme angular positions of the roll, and a third stop arranged to arrest the movement of said member in a position between the two stops so as to adjust the roll into an intermediate predetermined angular position.

5. A skiving machine having, in combination, a knife, a feed roll, a member movement of which varies the relative angular position of the knife and roll, said member having in it a recess, two stops serving as limits to the movement of said member so as to predetermine the two extreme angular positions of the knife and roll, and a third stop adapted to engage the recess in said member whereby said member may be held in a position intermediate the two first-named stops.

FLOYD W. BACKUS.
